(57) **CLAIM**

The ornamental design for a food processing and serving area for a restaurant, as shown.

DESCRIPTION

FIG. 1 is a right side elevational view of the food processing and serving area for a restaurant according to my new design.

FIG. 2 is a left side elevational view thereof.

FIG. 3 is a top plan view thereof.

FIG. 4 is a front elevational view thereof.

FIG. 5 is a rear elevational view thereof; and,

FIG. 6 is a perspective view of my new design as seen from the front right corner thereof.
